UNITED STATES PATENT OFFICE

2,449,389

VENTILATING WINDOW

Walter Kiesewetter, Ferndale, Mich.

Application August 27, 1945, Serial No. 612,970

2 Claims. (Cl. 98—88)

1.

This invention relates to building construction and has particular reference to windows for houses and other buildings.

An object of the invention is to generally improve windows, and to provide a device of that character which can be cleaned and otherwise serviced entirely from the inside of the house.

Another object of the invention is to provide a window through which ventilation may be had in various degrees throughout the full length of the window, even during a rain storm.

Another object of the invention is the provision of a window constructed and arranged in such manner that it is comparatively easy to replace broken glass, and to install the glass without the necessity of using putty or the like.

Another object of the invention is the provision of a window which may be adjusted for various degrees of ventilation and locked in any desired position.

Another object of the invention is the provision of a window constructed and arranged in such manner that even when fully opened, it would be impossible for an intruder to enter the house without breaking the glass.

The foregoing and other objects and advantages of the invention will become more apparent as the description proceeds, reference being made from time to time to the accompanying drawings forming part of the within disclosure, in which drawings:

Fig. 1 is a front elevation, with parts broken away, of a window embodying my invention.

Fig. 2 is a side elevation of the device illustrated in Fig. 1, with parts broken away, showing the window in closed position.

Fig. 3 is a fragmentary detail of the device illustrated in Fig. 2, showing the window in open position.

Fig. 4 is a section taken substantially on the line 4—4 of Fig. 2.

Fig. 5 is a section taken substantially on the line 5—5 of Fig. 3.

Referring now more particularly to the drawings, it will be understood that in the embodiment herein disclosed, my improved device consists of side jambs 7 and 8, head jamb 9, sill 10, and blind stops 11, 12, 13, 14, 15, 16, 17, and 18, all of which may be secured together and mounted in the wall of a building in conventional manner.

Mounted for rotation in suitable apertures in the side jambs 7 and 8 are a plurality of spaced and aligned pivots 19, to the inside end of each of which is securely mounted a channel member

20, adapted to support the panes of glass 21. Each pane of glass 21 is preferably made of two layers of safety glass (Fig. 5), the layers being arranged in staggered relation, so that when the window is closed, as shown in Figs. 1 and 2, there is an overlapping of the window panes as indicated at 22 (Fig. 2), to effect a weather seal.

10 The outside end of each pivot 19 is fixed to an arm 23 (Fig. 2), the arms 23 being locked to the pivots 19 by means of nuts 24, or by other suitable means. The arms 23 are preferably connected to one another by spring members 25, so that they may be worked in unison, yet be provided with a certain degree of resiliency to insure against breakage of the arms or the glass controlled thereby, in the event any of the elements should bind.

20 The upper and lower arms 23 on each side of the window are connected to rocker arms 26 and 27 (Fig. 2). The rocker arms 26 at the top are fixed to the ends of a rod 26A, and are adapted to rotate therewith. The rocker arms 27 at the bottom are pivoted as at 28, and are provided with racks 29, which are adapted to engage the pinions 30, which in turn engage the worm gears 31 of a conventional assembly such as employed in opening and closing steel windows and the like.

25 30 The worm gear 31 is adapted to rotate by means of a crank 32, which is adapted to be inserted in a suitable socket 33 carried at the end of the worm gear 31. The upper rocker arms 26 and the lower rocker arms 27 are connected by means of chains 34, and move in unison.

35 It will be seen, therefore, that when the worm gear 31 is rotated by means of the crank 32, the rocker arm 27 will move under the influence of the rack 29 and the pinion 30, causing the rocker arm 26 to move at the same time. When the rocker arms 27 rock in one direction, the rocker arms 26 will be similarly rocked by means of the chains 34; this will cause the upward movement 40 of the arms 23, causing the window panes 21 to open. When the rocker arms 27 are rocked in the opposite direction, it will cause the arms 23 to be rocked downwardly under the influence of the springs 25, whereupon the panes will be moved into a closed position.

45 It will be seen, therefore, that with this arrangement the several panes comprising the window may be locked to any degree of open position, and may be held there in locked position.

50 In Figs. 4 and 5, I illustrate the manner in

which a screen assembly 35 may be positioned on the inside of the window frame. In order to accommodate the screens 35, the side jambs 7 and 8 are slotted as at 36, so that the screens 35 may be inserted back of the blind stops 11 and 12. I prefer to have the slot 36 comparatively deep in one of the side jambs 7 or 8, so that the frame of the screen 35 may be inserted a sufficient distance, so that the opposite side of the screen will clear the blind stop adjacent thereto, and may be inserted behind the last-named blind stop. The screen may be removed by reversing the process.

It will, therefore, be seen that I have devised a novel window arrangement whereby various degrees of ventilation may be had during a rain.

Having described my invention, what I claim and desire to secure by Letters Patent is:

1. In a device of the character described, including a frame adapted to be mounted in a window opening, and having a plurality of panels of glass pivotally mounted therein, the combination of an arm secured to each panel pivot, coil springs connecting the adjacent arms, rocker arms at the top and bottom of each frame, a chain connect-

ing the upper rocker arm to the lower rocker arm, and linkage connecting the upper rocker arm to one of said first named panel pivot arms, and linkage connecting the lower rocker arm to another of said panel pivot arms.

2. The combination defined in claim 1, in which the said lower rocker arm has a rack thereon adapted to engage a pinion which is rotatable by means of a crank extending beyond the edge of said frame.

WALTER KIESEWETTER.
